ANTENNA HOUSING

Edward B. McMillan, Boston, and Henry J. Riblet, Cambridge, Mass., assignors, by mesne assignments, to the United States of America as represented by the Secretary of War

Application August 30, 1945, Serial No. 613,604

3 Claims. (Cl. 250—33)

1

The present invention relates to housings and more particularly to housings for electromagnetic energy radiating devices.

In many applications of radio apparatus it is desirable to enclose that portion of the apparatus which serves to radiate energy into space in order to protect it from the effects of weather, rough handling or accidental blows, wind or other fluid pressures, and the like. The practicality of and necessity for such a housing increases as the wavelength of the transmitted energy decreases since an extremely high frequency transmitter will usually require a small, delicate antenna.

Accordingly, it is one object of this invention to provide a housing for radio antennas.

Another object is to provide a streamlined antenna housing for use in a rapidly moving fluid medium.

Still another object is to provide an antenna housing which will permit the radiation pattern of the antenna to be relatively undisturbed.

An additional object of the present invention is to provide a new and improved antenna housing that will have provision for balancing its electrical characteristics in various directions to suit the radiation pattern of the antenna.

These and further objects of the invention will be apparent to those skilled in the art upon reference to the following specification, claims, and to the drawings in which:

Fig. 1 is a longitudinal cross-sectional view of one embodiment of the invention; and

Fig. 2 is a transverse cross-sectional view of the housing shown in Fig. 1.

Similar reference numerals pertain to the same parts throughout the drawings.

The antenna housing shown and described hereinafter is especially adapted for use with airborne, extremely high frequency radio apparatus, although the general scope of the invention is not necessarily limited to such an application.

Two considerations are paramount in the design and construction of an enclosure for any type of electromagnetic energy radiator. The first is the mechanical strength of the material used, in order that the housing may perform its protective function, and the second is the electrical characteristic of the material, in order that the radiation pattern of the radiator will not be impaired.

Referring now to Fig. 1, a shell, or skin, 5 of an at least partially wave-transparent material is formed into a desired shape, which in this case is that of a tube with a streamlined cross-section,

2

This skin material is chosen chiefly for its mechanical qualities. It would be possible to construct the housing entirely of this substance; however it has been found that the radiation pattern of the antenna would suffer by reason of the unsatisfactory electrical characteristics of the material.

A compromise is made by making skin 5 thick enough to be reasonably rigid and thin enough so that the electrical pattern of the radiated energy is relatively undisturbed. To strengthen the housing further it is filled with a low-density material 6 which is inferior to the substance of which shell 5 is composed in strength, but superior to it in dielectric characteristics.

A hole 7 is drilled into the filler material to receive an antenna and may be lined with a sheet 8 of the same material of which skin 5 is made. Due to the streamlined shape of the housing, energy emitted from the antenna will encounter different thicknesses of solid material depending upon the radial direction in which it is propagated. This can be seen more clearly in Fig. 2 in which a transverse section of the housing of Fig. 1 taken along the line 2—2 is shown. Clearly, radiation toward the blunt and wide front edge of the housing will pass through less thickness of dielectric material than radiation toward the tapered rear, and radiation toward the sides will encounter even less. Since the impedance presented to the radiant energy is closely related to the thickness of dielectric substance through which it must pass, it can be seen that the radiation pattern of the antenna will be adversely altered.

Therefore holes or cavities 10, 11, 12, 13, 14, 15, 16, and 17 are bored into the filler material in such a fashion as to substantially equalize the thickness of dielectric material in every direction radial to the antenna.

Plugs 20, 21, 22, 23, 24, 25, 26, and 27 are inserted into the equalizing holes at certain non-critical points such as the center and the open end, as determined by the standing wave pattern on the antenna itself, in order to strengthen the structure. Finally, a retaining plug 30 is inserted into the end of the housing in order to hold the filler material firmly in place.

In practice, it has been found that a material suitable for skin 5 is a laminate of Fiberglas with a styrene copolymer and the filler material may be satisfactorily composed of low density Hycar OR, which is a compound of synthetic rubber and other substances. Any suitable means may be provided for securing the housing

to the article intended to support and couple it. It will be recognized by those skilled in the art that the full scope of the invention is not necessarily defined precisely by the details of the embodiment described hereinabove, but departures may be made therefrom without exercise of inventive ingenuity. Hence, all such modifications and adaptations are claimed as may fall fairly within the spirit and scope of the herein-after appended claims.

What is claimed is:

1. A housing structure for an electromagnetic energy radiator comprising, a relatively thin shell of partially wave-transparent material and of quasi-streamlined transverse contour uniformly distributed throughout its longitudinal axis, a solid substance filling said shell and of relatively low density but relatively superior dielectrically to said material and permeated with holes therein in predetermined directions, areas and lengths to equalize their inherent dielectric effects in designated radial directions, one of said holes being sized and situated in said substance for the placement of an antenna therein, said holes and substance being arranged about said antenna as to provide a substantial equalization of the attenuation by the radiant energy emitted from said antenna through said structure.

2. A housing structure for an electromagnetic energy radiator comprising, a relatively thin shell of substantially wave-transparent material and of quasi-streamlined transverse contour uniformly distributed throughout its longitudinal axis, a substance filling said shell and of relatively low density and thickly deposited in said shell but relatively superior dielectrically as compared with said shell, said substance being permeated with parallel cavities therein in predetermined directions to equalize the inherent dielectric re-

sistivity in designated radial directions, one of said cavities being situated among said other cavities in said substance for the longitudinal placement of an antenna therein, said cavities and substance being arranged to provide a substantial equalization of the attenuation by the radiant energy emitted from said antenna through said structure and means for closing the open portions of said cavities.

- 10 3. A housing for an antenna comprising a tubular skin or relatively thin dielectric material, and a filler of dielectric material within said skin and surrounding said antenna, said skin being asymmetrically disposed relative to said antenna 15 and said skin having greater structural strength than said filler and said filler having better dielectric characteristics than said skin, and said filler being pierced by holes so disposed and shaped that the effective thickness of the filler in every 20 radial direction from the antenna is substantially the same, whereby the radiation pattern of the antenna is substantially undistorted by the asymmetrical configuration of the housing.
